CLAIM

The ornamental design for an oscillating sprinkler, as shown and described.

DESCRIPTION

FIG. 1 is a perspective view of an oscillating sprinkler, according to my new design;

FIG. 2 is a top view of the oscillating sprinkler shown in FIG. 1;

FIG. 3 is a bottom view of the oscillating sprinkler shown in FIG. 1;

FIG. 4 is a left side view of the oscillating sprinkler shown in FIG. 1;

FIG. 5 is a right side view of the oscillating sprinkler shown in FIG. 1;

FIG. 6 is a front side view of the oscillating sprinkler shown in FIG. 1; and,

FIG. 7 is a rear side view of the oscillating sprinkler shown in FIG. 1.

The broken lines shown represents portions of a oscillating sprinkler and form no part of the claimed design.

1 Claim, 5 Drawing Sheets
